US0D1042598S

(12) **United States Design Patent** (10) **Patent No.:** **US D1,042,598 S**
(45) **Date of Patent:** **** Sep. 17, 2024**

(54) **PROJECTOR**

(71) Applicant: **LG ELECTRONICS INC.**, Seoul (KR)

(72) Inventors: **Daesung Lee**, Seoul (KR); **Daihyung Ryu**, Seoul (KR); **Hyunseung Seo**, Seoul (KR); **Hewon Kihl**, Seoul (KR); **Youngho Kim**, Seoul (KR)

(73) Assignee: **LG ELECTRONICS INC.**, Seoul (KR)

(***) Term: **15 Years**

(21) Appl. No.: **35/517,286**

(22) Filed: **Nov. 23, 2022**

(80) **Hague Agreement Data**

Int. Filing Date: **Nov. 23, 2022**

Int. Reg. No.: **DM/225340**

Int. Reg. Date: **Nov. 23, 2022**

Int. Reg. Pub. Date: **May 26, 2023**

(30) **Foreign Application Priority Data**

Jul. 1, 2022 (KR) 30-2022-0026543

(57) **CLAIM**

The ornamental design for a projector, as shown and described.

DESCRIPTION

The patent or application file contains at least one drawing executed in color. Copies of this patent or patent application publication with color drawing(s) will be provided by the Office upon request and payment of the necessary fee.

1. Projector

1.1 : Front perspective

1.2 : Back perspective

1.3 : Front

1.4 : Back

1.5 : Left

1.6 : Right

1.7 : Top

1.8 : Bottom

1.9 : Reference view

1.10 : Reference

1.11 : Reference

Reproductions 1.9 and 1.11 show a rotated state of the projection part from a different angle respectively; reproduction 1.10 illustratively shows an illuminated state of the lighting that forms no part of the claimed design; the broken lines shown in the reproductions depict portions of the projector that form no part of the claimed design; the shading lines are used to show the surface of the claimed design and do not represent its surface ornamentation.
